HOIST

George W. McCollum, Downers Grove, Ill.

Application March 16, 1936, Serial No. 69,131

10 Claims. (Cl. 254—170)

The present invention relates generally to hoists, chain blocks and similar apparatus, and is particularly concerned with the provision of new and improved means associated with the raising and lowering mechanism for automatically retaining the load in a given position.

Heretofore, various forms of screw hoists and gear hoists have been provided for the purpose of raising and lowering, or moving, loads and the like and each type has its advantages and disadvantages. Gear hoists, using spur gears or similar mechanism, have as a rule been somewhat more efficient than hoists operating on the worm wheel and screw principle, commonly called screw hoists. Usually hoists of the latter type have an efficiency of around 35 percent, while the efficiency of gear hoists have as a rule been substantially greater. However, gear hoists are usually considerably heavier than screw hoists and, in addition, have required special ratchet and similar mechanism to prevent the load from running backwardly. Screw hoists, on the other hand, usually operate without ratchets and the like to hold the load securely in position, due principally to the low efficiency of the worm and worm wheel in the first place and the considerable amount of friction which serves to prevent the worm wheel from driving the worm backwardly.

With these and other factors in mind, the principal object of the present invention is the provision of a screw or worm hoist of high efficiency and light weight, and in which special means of simple and sturdy construction has been provided for automatically preventing the load from running backwardly unless the driving means is actually operated in that direction. More specifically, another object of the present invention is the provision of new and improved brake mechanism associated with a simple hoist of the screw or worm type in which the end thrust of the worm, arising by virtue of the reaction of the load thereon, is utilized for automatically controlling a brake or lock which securely holds the load in any position to which it may be moved.

A further object of the present invention is the provision of a hoist of the screw type having a worm shaft which is axially shiftable in one direction under the reaction of the load and in the other direction under the reaction of driving means, with a simple form of brake mechanism actuated by the axial movements of the worm shaft for holding the load in any given position but which is adapted to be released when-

ever the load is to be driven, either in one direction or the other.

These and other objects and advantages of the present invention will be apparent to those skilled in the art after a consideration of the following detailed description of the preferred embodiment, taken in conjunction with the accompanying drawing illustrating such embodiment.

In the drawing:

Figure 1 is a vertical section taken substantially midway through a hoist embodying the principles of my invention; and

Figure 2 is a fragmentary perspective, taken at an enlarged scale, illustrating the cam mechanism carried by the worm shaft and driving shaft for the purpose of shifting the worm shaft to release the brake mechanism when the driving means is operated.

Referring now more particularly to Figure 1, the reference numeral 10 indicates in its entirety a casing or frame usually consisting of two separable halves 11 secured together by a plurality of bolts 12. The upper portion of the casing halves 11 are formed with an opening 15 which receives the reduced shank portion 16 of a top hook 17, the shank 16 having an enlarged head 18. The top hook 17 is adapted to be supported by a chain or the like from any suitable supporting member, such as a girder or the like and, in turn, serves to support the casing 10 and the associated lifting mechanism, as well as the load carried by the latter.

A worm wheel shaft 20 is journaled for rotation in the central portion of the casing 10 and at its outer ends, which project exteriorly of the casing, carries two load sheaves 21 of more or less conventional construction, there being one at each side of the casing, and usually each supports a load chain 22 trained thereover and having a load receiving portion 22a extending downwardly to which the load to be raised is connected in any suitable manner, usually by a bottom hook (not shown) or the like supported by the two load chains. Usually, the other end of each of the load chains 22 is connected to the casing 10, as by having one link disposed over one of the casing bolts 12.

A worm wheel 30, usually of bronze or the like, is disposed within the casing 10 and fixedly secured to the worm wheel shaft 20 by any suitable manner, such as a key 31 or the like. Meshing with the teeth of the worm wheel 30 is a worm 34 formed on a tubular worm shaft 35 of special construction, usually of steel, the worm teeth being preferably, but not necessarily, formed

integrally with the tubular worm shaft 35. The tubular worm shaft is journaled for rotation in the lower portion of the casing 10, as by being mounted over a driving shaft 38 which has a reduced end 39 disposed in a bearing opening formed in the casing 10. The reduced end 39 provides a shouldered portion 40 which is arranged to be disposed in thrust engagement with a boss 41 formed on the associated wall portions 10 of the casing 10. The other end of the driving shaft 38 extends exteriorly of the casing and also exteriorly of the end 35a of the tubular worm shaft 35, which also extends exteriorly of the casing through a suitable bearing opening in the wall 15 of the casing 10 opposite the portion 41 thereof.

Adjacent the end of the driving shaft 38 having the reduced portion 39 is provided a plurality, usually three, lugs 50 which have ends serving as oppositely angled cam surfaces 51 and 52, and 20 these cam surfaces cooperate with companion cam surfaces 53 and 54 formed in notches 55 cut in the associated end of the tubular worm shaft 35. As best shown in Figure 1, the lugs 50 are each 25 more narrow than the circumferential dimension of the worm shaft notches 55 so that the driving shaft 38 is capable of limited rotation in either direction, relative to the tubular worm shaft 35, from the position shown in Figure 1 before engaging the ends of the notches 55. However, such 30 relative rotation of one shaft with respect to the other serves to shift the tubular worm shaft 35 axially, due to the inclination of the cooperating cam surfaces 51, 53 or 52, 54, depending upon in 35 which direction the relative rotation between the shafts occurs.

The outer extended end 35a of the tubular worm shaft 35 carries a brake plate 60 suitably keyed, as at 61, or otherwise fixedly secured to the worm shaft, and the brake plate 60 carries a 40 friction member 62 suitably riveted or otherwise secured thereto. A stationary brake plate 66 is fastened, as by screws 67 or any other suitable means, to the casing 10 in nonrotatable relation. Since the member 60 is fixed to the worm shaft 45 35 and the member 66 is fixed to the casing, when these brake parts are forced into engagement with one another, rotation of the worm shaft 35 is prevented.

Any suitable means may be provided for actuating the drive shaft 33 such as, for example, an 50 electric motor or other source of power, but for purposes of simplicity I have shown a hand wheel 70 as mounted on the outermost end of the driving shaft 38. The circumferential portion of the hand wheel 70 is suitably formed to receive a hand chain 71 which may be pulled by the operator so as to rotate the wheel 70 in one direction or the other. The wheel 70 is securely fixed to the driving shaft 38 by any suitable means, such as a 55 set screw, key or the like. While for purposes of simplicity I have shown a hand wheel associated with the driving shaft 38, it is to be understood that the wheel 70 represents any form of driving means for actuating the shaft 38. It is to be 60 noted that there is a space 72 between the hand wheel 70 and the outer end of the tubular worm shaft 35 and the associated rotatable brake member 60. This is for the purpose of accommodating the axial movement of the tubular worm shaft 35 referred to above.

In operation, when a load is supported on the 65 portions 22a of the load chains 22, the weight of the load tends to rotate the worm wheel 30 in the direction of the arrow shown in Figure 1. This 70 exerts a thrust on the worm shaft 35, tending

to shift the same axially toward the right as viewed in Figure 1, and causes the lugs 50 to bottom in the notches 55, and in turn permits the brake plate 60 to be forced up against the stationary brake plate 66 fixed to the casing 10. 5 There is sufficient clearance between the lugs 50 and the bottoms of the notches 55 that the reaction of the load carried on the chains 22 is effective to hold the cooperating brake plates in frictional engagement with sufficient force to 10 prevent the lowering of the load. According to the principles of the present invention, the teeth on the worm and worm wheel are cut so as to secure a greater efficiency than has heretofore been possible so that, if it were not for suitable 15 braking means, the load reacting through the worm wheel 30 and against the worm 34, would rotate the latter. However, the reaction of the load in shifting the tubular worm shaft 35 to the right, as viewed in Figure 1, and causing the co- 20 operating brake parts to be brought into engagement, effectively serves to lock the load in any position.

When it is desired, for example, to raise the 25 load, the hand wheel 70 is actuated in the proper direction. Remembering that the driving shaft 38 is rotatable relative to the tubular worm shaft 35, the first angular movement of the shaft 38 30 brings the cooperating cam surfaces on the lugs 50 and the notched end of the worm shaft 35 into engagement so that as the hand wheel 70 is turned in the desired direction, the first effect is to shift the tubular worm shaft 35 in a direction against the reaction of the supported load and 35 opposite to the direction in which the reaction of the load tends to shift the tubular worm shaft 35. Axial movement of the shaft 35 in said opposite 40 direction, that is, to the left as viewed in Figure 1, thus serves to release the cooperating brake members 60 and 66 so that at this time continued rotation of the shaft 38 will then rotate the worm 34 45 and shift the load, either upwardly or downwardly, depending upon in which direction the hand wheel 70 is turned. In this connection it is to be observed that the lugs 50 and notches 55 have 50 surfaces inclined in both directions, so that, regardless as to the direction in which the shaft 38 is rotated, the first angular movements thereof cause the tubular worm shaft 35 to be moved 55 axially so as to release the brake means. Thereafter, continued rotation of the driving shaft 38 in that direction rotates the lifting worm wheel 30 and the load connected therewith. As is obvious, in lowering the load, for example, the hand wheel 70 is first turned in that direction, and this 60 shifts the worm shaft 35 and releases the brake means. Thereafter, it is then merely necessary to keep the hand wheel 70 and driving shaft 38 ahead of the rotation of the worm shaft 35. The lowering of the load may, of course, be terminated at any time by stopping the hand wheel 70, whereupon the reaction of the load supported on the chains 22 will become immediately effective to shift the tubular worm shaft 35 to the right so 65 as to bring the cooperating brake parts into engagement to thereby prevent further lowering of the load, the only angular movement of any of the associated parts in thus locking the load being that sufficient to bring the lugs 50 from 70 one end of the slots 55 to the intermediate portion thereof.

It is to be noted that by virtue of the construction described above, I am enabled to make use 75 of an efficient form of screw and worm mecha-

nism of the reversible type and that it is not necessary to rely upon friction between these parts for holding the load in any given position. Thus, the efficiency of a construction embodying

5 the principles of the present invention may be practically doubled as compared with previous forms of screw hoists. It is also to be observed that the locking mechanism is engaged with a force that is proportional to the load reaction, 10 and hence in no instance is the braking force greater than necessary to hold the load in position. Mention was made above of the fact that the hand wheel 70 represents any form of driving means for the shaft 38. In many constructions, 15 a power operation, rather than hand operation, is preferred. In this connection, certain features of the present invention are especially advantageous. For example, considering that the hand wheel 70 is replaced by an electric motor, whenever the power is shut off, the brake mechanism 60, 66 not only serves to bring the load to rest but, in addition, serves also to snub the motor and thus prevents any momentum in the latter from carrying the load downwardly or upward 20 farther than is desired. In many hoists of prior construction employing motor drives, some form of brake mechanism was found necessary to be applied to the motor shaft, but according to the 25 principles of the present invention, such brake mechanism is no longer necessary.

While I have shown and described above the preferred construction in which the principles of the present invention have been embodied, it is to be understood that my invention is not to be limited to the particular details shown and described above, but that, in fact, widely different means may be employed in the practice of the broader aspects of my invention.

What I claim, therefore, and desire to secure 40 by Letters Patent is:

1. A hoist comprising a frame, a worm wheel shaft journaled for rotation on said frame, a load moving worm wheel on said shaft, a worm meshing with said worm wheel, a stationary brake 45 member carried by said frame, and a cooperating brake member carried by said worm and actuated into braking engagement with said stationary brake member by the end thrust of said worm under the reaction of a load connected with 50 said worm wheel for holding the worm against rotation.

2. A hoist comprising a frame, a worm wheel shaft journaled for rotation on said frame, a load moving worm wheel on said shaft, a worm meshing with said worm wheel, a stationary brake member carried by said frame, a cooperating 55 brake member carried by said worm and actuated into braking engagement with said stationary brake member by the end thrust of said worm under the reaction of a load connected with 60 said worm wheel for holding the worm against rotation, driving means for said worm, and means actuated by said driving means for counteracting the end thrust of said arm to release said brake means.

3. A hoist comprising a frame, a worm wheel shaft journaled for rotation on said frame, a load moving worm wheel on said shaft, a worm meshing with said worm wheel, a stationary 70 brake member carried by said frame, a cooperating brake member carried by said worm and actuated into braking engagement with said stationary brake member by the end thrust of said worm under the reaction of a load connected with 75 said worm wheel for holding the worm against

rotation, driving means for said worm, and means actuated by said driving means in each direction of rotation thereof for counteracting the end thrust of said worm to release said brake means.

4. A hoist comprising means serving as a frame, 5 a load supporting worm wheel journaled thereon, a driving shaft journaled in said frame, a tubular worm shaft mounted for axial movement on said driving shaft and including a worm meshing with said worm wheel, cooperating brake parts 10 carried by said casing and said tubular worm shaft, cooperating cam elements carried by said driving shaft and said tubular worm shaft providing for the axial movement of said worm shaft on said driving shaft under the reaction of a 15 load connected with said worm wheel for bringing said brake parts into engagement to lock the load in position, and means for driving said drive shaft, the reaction of said driving means operating through said cooperating cam elements for 20 shifting said tubular worm shaft against said load reactance so as to release said brake parts and to permit said worm shaft and worm wheel to be rotated by said driving means.

5. A hoist comprising means serving as a frame, 25 a load supporting worm wheel journaled thereon, a driving shaft journaled in said frame, a tubular worm shaft mounted for axial movement on said driving shaft and including a worm meshing with said worm wheel, cooperating brake parts 30 carried by said casing and said tubular worm shaft, the reaction of the load connected with said wheel serving to shift said tubular worm shaft in a direction to engage said brake parts, whereby said load is locked in position, means for driving 35 said drive shaft, and cooperating cam elements on said driving and worm shafts and operable when said drive shaft is rotated in either direction relative to the worm shaft for first shifting the latter against the reaction of the load for 40 releasing said brake parts and then rotating said worm shaft to shift said load.

6. A hoist comprising means serving as a casing, a worm and worm shaft of the reversible type journaled for rotation thereon, said worm 45 shaft being shiftable axially and extending to a point exteriorly of the casing at one end, a stationary brake member carried by said casing means, an axially movable brake member fixed to the outer end of said axially shiftable worm 50 shaft, the reaction of a load connected with said worm wheel tending to shift said worm shaft axially and to bring said brake plates into braking engagement to hold the load in position, and driving means for driving said worm shaft including means reacting against said casing for 55 axially shifting said worm shaft to release said brake plates and permit said worm shaft to be rotated by said driving means.

7. A hoist comprising a load moving worm 60 wheel, a worm meshing with said worm wheel and shiftable endwise by a load on the worm wheel, brake means applied by the endwise shifting movement imparted to the worm by a load on the worm wheel for holding the load against 65 lowering movement by the weight thereof, means for turning the worm to move the load, and cooperating cam elements actuated by said worm turning means in each direction of turning movement thereof for shifting the worm endwise to 70 release said brake means.

8. A hoist comprising a load moving worm wheel, a worm meshing with said worm wheel, means for turning the worm to move the load, 75 brake means applied by the end thrust imparted

to the worm by a load on the worm wheel for preventing retrograde movement of the load, and cooperating cam elements actuated by said worm turning means in each direction for releasing said brake means.

5. 9. In combination, a shaft, a tubular member surrounding said shaft, a worm on said tubular member, a worm wheel meshing with said worm, a stationary brake member, and a cooperating 10 brake member movable into and out of engagement with said stationary brake member by endwise movement of said tubular member.

10. In combination, a shaft, a tubular member surrounding said shaft, a worm on said tubular member, a worm wheel meshing with said worm, a stationary brake member, a cooperating brake member movable into and out of engagement with 5 said stationary brake member by endwise movement of said tubular member, a driving shaft extending through said tubular member, and co-operating means on the tubular member and said shaft for shifting said tubular member endwise 10 to release said brake means.

G. W. McCOLLUM.
